[57] ABSTRACT

A process for producing isopentane which comprises: (a) isomerizing a C₆-rich hydrocarbon fraction in an isomerization zone to obtain at least isopentane and C₄ alkanes, (b) fractionating the isopentane from the C₄ alkane to obtain an isopentane product, (c) disproportionating at least a portion of the C₄ alkanes in a C₄ disproportionation zone to obtain at least n-pentane and C₃ hydrocarbons, and (d) isomerizing the n-pentane in the isomerization zone. Preferably, the isomerization zone uses a sulfactive isomerization catalyst so that the isomerization zone serves not only an isomerization function but also a purification function for subsequent disproportionation.

HEXANE CONVERSION

BACKGROUND OF THE INVENTION

The present invention relates to a combination process involving isomerization of saturated hydrocarbons. More particularly, the present invention relates to isomerization operated in combination with saturated hydrocarbon disproportionation, and preferably with integrated common fractionation facilities.

Isomerization is a well-known and frequently used step in petroleum refining. It enables the adjustment of the octane number upwards by converting normal paraffins, such as normal hexane, to isoparaffins, such as 2,2-dimethylbutane. A blend of various isomeric paraffins provides a gasoline which has a higher octane number than a gasoline consisting of normal paraffins. Isomerization is generally performed by passing isomerizable hydrocarbons together with hydrogen through a reaction zone containing an isomerization catalyst. The hydrogen-to-hydrocarbon mol ratio varies within a wide range, generally from 0.05:1 to 5:1, preferably within the range of about 0.5:1 to 2:1 for pentanes and hexanes and 0.1:1 to 1:1 for butanes. The reaction temperature will depend upon the specific hydrocarbons being isomerized and the nature and type of catalyst employed. Hydrocarbon streams consisting chiefly of pentanes and hexanes are usually isomerized at temperatures within the range of 200-900°F. The isomerization, normally effected under pressure, may be carried out in the liquid or vapor phase. Generally, pressures within the range of 300-1,000 psig have been used. A liquid hourly space velocity (LHSV), that is, the volume of liquid charged per hour per volume of catalyst, within the range of 0.5 to 10.0 and preferably within the range of about 0.75 to 4.0 is employed.

Various catalysts have been suggested for use in isomerization processes. In general, the isomerization can be effected at low temperatures (ca. 300°F.) with a Friedel-Crafts catalyst, such as aluminum chloride, or at high temperatures (ca. 750°F.) with a supported metal catalyst, such as platinum on halogenated alumina or silica-alumina. Thermodynamic equilibrium for isoparaffins is more favorable at low temperatures; however, the low-temperature-process has not received wide application because the Friedel-Crafts catalyst is quite corrosive and therefore expensive metals or alloys must be used. Of the high temperature isomerization processes, the noble metal catalysts such as platinum or palladium are perhaps considered to be the most effective.

As indicated in U.S. Pat. Nos. 2,951,888 and 3,472,912, minor amounts of sulfur compounds in the feed to isomerization processes are harmful for the typical isomerization processes. Catalysts used in typical isomerization processes include composites of a hydrogenating component on an amorphous acidic silica-alumina support and more usually composites comprising halogenated alumina or aluminum, either of which latter composites are herein referred to as halogenated aluminum catalysts.

According to U.S. Pat. No. 2,951,888, a C₄-C₇ paraffinic feedstock is desulfurized to a sulfur content less than 1 ppm so that better results are achieved in hydroisomerization of the paraffinic feedstock with a catalyst selected from the group consisting of nickel, nickel-molybdenum, and palladium, supported on an

acidic silica-alumina support containing 50-90 percent silica, at a temperature of 650°-800°F., pressure of 100-1,000 psig, and hydrogen-hydrocarbon mol ratio of 0.5-5.0.

5 U.S. Pat. No. 3,472,912 also discloses an over-all combination process involving hydrotreating and isomerization wherein a nickel molybdenum-on-alumina catalyst is used under hydrotreating conditions to remove sulfur from C₄-C₇ saturated hydrocarbons so

10 that the hydrocarbons can be isomerized with increased life for the isomerization catalyst. Preferred isomerization catalysts according to the process of U.S. Pat. No. 3,472,912 are platinum-alumina composites activated by the addition of carbon tetrachloride (thereby resulting in a catalyst which is herein classified as a catalyst containing halogenated aluminum).

Recently, catalysts comprising either natural or synthetic crystalline aluminosilicates have been suggested for isomerization processes. Included among the 15 crystalline aluminosilicates which have been suggested are the type 'X' and type 'Y' silicates, mordenite, and layered aluminosilicates such as described in Granquist U.S. Pat. No. 3,252,757.

20 U.S. Pat. No. 3,507,931, titled "Isomerization of Paraffinic Hydrocarbons in the Presence of a Mordenite Catalyst" discloses the isomerization of straight run distillates rich in C₄-C₆ normal paraffins using a catalyst having a high silica-to-alumina ratio, preferably above 20:1, and operating the isomerization reaction at relatively low temperatures, such as 250°-400°F.

25 U.S. Pat. Nos. 3,280,212 and 3,301,917 also disclose hydroisomerization processes using crystalline aluminosilicate-type catalysts.

30 As indicated above, the present invention is directed to both isomerization and disproportionation.

35 The term "disproportionation" is used herein to mean the conversion of hydrocarbons to new hydrocarbons of both higher and lower molecular weight. For example, butane may be disproportionated according to the reaction:

40 45 As can be seen from the above disproportionation reaction, the butane is in part converted to a higher molecular weight hydrocarbon, namely, pentane. Various processes have been suggested for converting hydrocarbons to higher molecular weight hydrocarbons.

50 55 U.S. Pat. No. 1,687,890 is directed to a process of converting low-boiling-point hydrocarbons into higher-boiling-point hydrocarbons by mixing a hydrocarbon vapor with steam and then contacting the steam-hydrocarbon mixture with iron oxide at temperatures in excess of 1,112°F. It is theorized in U.S. Pat. No. 1,687,890 that the following reactions may be involved to a greater or lesser extent:

60 65 "1. Paraffin hydrocarbons on being brought into contact with ferric oxide at elevated temperatures are oxidized or dehydrogenated, forming unsaturated hydrocarbons.

"2. Unsaturated hydrocarbons of low molecular weight polymerize into unsaturated hydrocarbons of higher molecular weight when subjected to elevated temperatures, the extent of polymerization depending upon the temperature and duration of treatment.

"...

"7. Unsaturated hydrocarbons are hydrogenated by nascent hydrogen."

Another process which has been proposed for converting hydrocarbons to higher molecular weight hydrocarbons is olefin disproportionation. Numerous methods and catalysts have been disclosed for the disproportionation of olefins. In most of these processes, the olefin is disproportionated by contacting with a catalyst such as tungsten oxide or molybdenum oxide on silica or alumina at a temperature between about 150°-1,100°F. and at a pressure between about 15 and 1,500 psia. These prior art processes have been directed to an effective method to convert essentially only olefins, not saturated hydrocarbons, to higher molecular weight hydrocarbons by disproportionation.

For example, in U.S. Pat. No. 3,431,316, an olefin disproportionation process is disclosed, and it is stated that, if desired, paraffinic and cycloparaffinic hydrocarbons having up to 12 carbon atoms per molecule can be employed as diluents for the reaction; that is, the saturated hydrocarbons are non-reactive and merely dilute the olefins which are the reactants.

A process for the direct conversion of saturated hydrocarbons to higher molecular weight hydrocarbons would be very attractive because in many instances saturated hydrocarbons are available as a relatively cheap feedstock. For example, in many instances, excess amounts of propane and/or butanes are available in an over-all refinery operation.

Processes which have been previously reported wherein saturated hydrocarbons are disproportionated include contact of saturated hydrocarbons with solid catalyst comprised of $AlCl_3$ on Al_2O_3 and contact of saturated hydrocarbons with a promoter comprised of alkyl fluoride and BF_3 . The use of the $AlCl_3$ solid catalyst was uneconomic because, among other reasons, the catalyst was non-regenerable. The use of alkyl fluoride and BF_3 was unattractive because of severe corrosion, sludge formation and other operating problems.

In the past it has been the practice to convert saturated hydrocarbons, particularly normal alkanes, to olefins as a separate or distinct step and then to disproportionate the olefins to valuable higher molecular weight hydrocarbons.

For example, in U.S. Pat. No. 3,431,316, saturated light hydrocarbons are cracked to form olefins, and then the olefins are separated from the cracker effluent and fed to a disproportionation zone wherein the olefins are disproportionated to higher molecular weight hydrocarbons. Thus, a separate step is used to obtain olefins because, according to the prior art, no economically feasible process is available for the direct disproportionation of saturated hydrocarbons.

U.S. Pat. No. 3,445,541 discloses a process for the dehydrogenation-disproportionation of olefins and paraffins, using a combined dehydrogenation and disproportionation catalyst. According to U.S. Pat. No. 3,445,541, a hydrocarbon feed which is either an acyclic paraffin or acyclic olefin having three to six carbon atoms is contacted with the catalyst at conditions of temperature and pressure to promote dehydrogenation and disproportionation. It is said that the process can be carried out at temperatures between 800°F. and 1,200°F.; however, the lowest temperature used for

processing a paraffin in accordance with any of the examples of U.S. Pat. No. 3,445,541 is 980°F., and typically the temperature used is between 1,040°F. and 1,125°F.

5 The high-temperature process disclosed in U.S. Pat. No. 3,445,541 is shown therein to result in only relatively low yields of saturated higher molecular weight hydrocarbons. The U.S. Pat. No. 3,445,541 process operates with a substantial amount of olefins in the 10 reaction zone and with about 10 to 50 volume percent or more olefins in the effluent from the disproportionation reaction zone. U.S. Pat. No. 3,445,541 does not disclose or suggest any advantages for disproportionation of hexanes and butanes in combination with C_5 and 15 C_6 isomerization.

SUMMARY OF THE INVENTION

According to the present invention, a process is provided for producing isopentane which comprises: (a) isomerizing a C_6 -rich hydrocarbon fraction in an isomerization zone to obtain at least isopentane and C_4 alkanes, (b) fractionating the isopentane from the C_4 alkanes to obtain an isopentane product, (c) disproportionating at least a portion of the C_4 alkanes in a C_4 disproportionation zone to obtain at least n-pentane and C_3 hydrocarbons, and (d) isomerizing the n-pentane in the isomerization zone.

The process of the present invention results in the 30 production of high-octane isopentane from low-octane hexane (such as normal hexane, which has an octane rating of about 26). The isopentane which is produced in the process of the present invention has an octane rating of about 92 and is particularly useful in high-octane unleaded or low-head-content gasolines.

Isomerization of C_6 hydrocarbons can be used to upgrade the octane rating of normal hexane-rich hydrocarbon fractions. However, the octane can be increased only to about 70-75 (motor octane) by isomerization because the main hexane isomers produced, namely, 2-methyl pentane and 3-methyl pentane, have an octane rating of only 73 and 75, respectively. Although increasing the octane rating of a C_6 fraction from the vicinity of about 26, which is the octane of normal hexane, to about 70-75 by isomerization to produce isohexanes represents a substantial increase, it is generally not a sufficient increase to produce high-octane gasoline components for use in unleaded or lead-free gasolines.

50 The C_6 -rich hydrocarbons also have been considered as feedstocks for catalytic reforming in order to reform the C_6 material into reasonably low volatility gasoline boiling range hydrocarbons in the 90+ octane range. However, the C_6 hydrocarbons have been found to make a relatively unattractive feedstock for catalytic reforming processes.

Thus, it is desirable to provide a process for upgrading C_6 -rich hydrocarbon fractions into 90+ octane rating components. The process of the present invention 60 achieves these desired results by the combination of isomerization with disproportionation. In addition, the isomerization step is particularly advantageously employed with the disproportionation step in the present invention as the isomerization step serves the dual function of (1) purifying C_6 -rich hydrocarbons which are subsequently disproportionated, and (2) isomerizing a portion of the C_6 hydrocarbons.

The isomerization zone serves to purify the feed for the disproportionation zone by converting sulfur compounds in the C₆-rich feed to the isomerization zone to hydrogen sulfide, which can be readily removed from the isohexane-rich effluent from the isomerization zone before the isohexane-rich effluent is fed to the disproportionation zone. The preferred catalyst used in the disproportionation zone is sensitive to even small amounts of H₂S, and H₂S will be formed in the disproportionation zone unless the organic sulfur compounds are substantially completely removed ahead of the disproportionation zone.

Also, the isomerization zone can serve to increase the amount of isopentane produced in the disproportionation zone by providing a branched-chain C₄ feed for the disproportionation zone. Using the preferred dual-function dehydrogenation-olefin disproportionation catalyst for the disproportionation zone, there is substantially no production (or depletion) of branched-chain hydrocarbons in the disproportionation reaction zone.

According to a preferred embodiment of the present invention, the isomerization zone is further integrated with the disproportionation zone by using common fractionation facilities, at least in part. The term "fractionation facilities" is used herein to mean distillation columns or the like and associated equipment.

The effluent from the C₅-C₆ isomerization zone is usually composed primarily of isobutane, normal butane, isopentane, normal pentane, isohexanes and normal hexane. However, there also is present minor or small amounts of propane and C₇+ hydrocarbons. It will, of course, be understood that the amount of these secondary hydrocarbons will depend upon several factors, including the composition of the feed to the isomerization zone, the type catalyst used in the isomerization zone (some isomerization catalysts have higher per-pass conversions but lower selectivities to the desired isopentane and isohexane products), and the temperature used in the isomerization zone (higher temperatures usually resulting in more light hydrocarbons such as propane). The effluent hydrocarbons from normal butane disproportionation according to the preferred embodiments of the present invention using the two-component disproportionation catalyst usually are primarily propane, normal butane, normal pentane, normal hexane and C₇+ hydrocarbons. However, there will also be minor or small amounts of isobutane, isopentane, and isohexane. The amounts of these iso- or branched-chain hydrocarbons will increase if increased amounts of isobutane are fed to the C₄ disproportionation step. Thus, it is particularly advantageous to use common fractionation facilities for the isomerization zone effluent hydrocarbons and the disproportionation zone effluent hydrocarbons when substantial amounts, for example more than 5 or 10 weight percent, isobutane is fed to the C₄ disproportionation zone because, in this instance, there is an increased amount of common hydrocarbons from both the isomerization zone and the disproportionation zone.

The fractionation facilities required for the effluent from the isomerization zone and for the effluent from the disproportionation zone can range from one or two columns up to about eight sequential columns. For example, a propane splitter to separate propane from

isobutane+; ar: isobutane splitter to separate isobutane from normal butane+; a normal butane splitter to separate normal butane from isopentane+; an isopentane splitter to separate isopentane from n-pentane+; a normal pentane splitter to separate normal pentane from isohexane+; an isohexane splitter to separate isohexane from normal hexane+; and a normal hexane splitter to separate normal hexane from C₇+. The fractionation of the aforementioned hydrocarbon cuts can be carried out in sequential separate columns or, at the other extreme, one column can be used similar to crude oil distillation with side streams being withdrawn from the column and stripped, if necessary. As indicated previously, the amounts of the various components present in the effluents from the isomerization zone and the disproportionation zone can vary. Thus, in some instances, only part of the fractionation for the two zones will be carried out in common fractionation facilities with the other part being carried out in separate fractionation facilities for the respective zones. Because there are usually substantial amounts of normal pentane and C₆ alkanes in the effluent hydrocarbons in both the isomerization zone and the disproportionation zone, it is particularly preferred to carry out the separation of normal pentane from C₆ alkanes in a distillation column common to both the isomerization zone and the disproportionation zone.

In the process of the present invention, the feed to the C₄ disproportionation zone can be a normal butane feed or a feed containing substantial amounts of isobutane in addition to normal butane. Usually it is preferred to feed isobutane as well as the normal butane to the disproportionation zone so as to produce isopentane (as well as normal pentane from the normal butane). Isopentane has a substantially higher octane than the isohexanes 2-methyl pentane and 3-methyl pentane, which are the primary isohexane products from C₆ isomerization using sulfactive isomerization catalysts and isomerization conditions (500°-800°F.) suitable for hydrodesulfurization.

As indicated above, one of the important purposes which the isomerization zone serves in the process of the present invention is to remove sulfur impurities from the C₆ fraction before the butanes are fed to the disproportionation zone. In broad scope, the process of the present invention can be applied to the isomerization and subsequent disproportionation of C₄-rich hydrocarbon streams which are essentially free of sulfur impurities as, for example, C₄ hydrocarbons contained in C₆ hydrocarbon streams obtained from a catalytic reforming unit. However, the process combination of the present invention has particular advantage when applied to C₆-rich hydrocarbon streams containing minor amounts of sulfur impurities, usually at least 5 ppm sulfur.

C₆ hydrocarbon cuts obtained by crude oil distillation, i.e., straight run C₆-rich hydrocarbon fractions, contain usually at least 5 ppm organic sulfur compounds (calculated as elemental sulfur by weight) and generally between about 20 and 500 ppm organic sulfur compounds. The isomerization zone can use a hydrotreating step ahead of the isomerization reaction zone catalyst as in the case of using halogenated aluminum-type catalysts, but it is preferred in the process of the present invention to use a crystalline aluminosil-

icate-type hydroisomerization catalyst, many of which catalysts we have found can be operated with several hundred ppm sulfur and frequently up to about 500 or 1,000 ppm sulfur in the feed without substantially decreasing the life of the hydroisomerization catalyst. Also, the crystalline aluminosilicate-type catalyst can be used to obtain relatively high yields of isohexane per pass at temperatures usually about 100°F. less than is required for a comparable isohexane yield using halogenated aluminum-type isomerization catalysts. Halogenated aluminum-type catalysts which are sensitive to sulfur poisons and thus not as preferred for use in the process of the present invention include the catalyst such as used in the butamer process described in the Oil and Gas Journal, Vol. 56, No. 13, Mar. 31, 1958, pp. 73-76, the BP isomerization process as described in Hydrocarbon Processing, Vol. 45, No. 8, Aug. 1966, pp. 168-170, and the liquid phase isomerization process described in Hydrocarbon Processing, Vol. 42, No. 7, July 1963, pp. 125-130.

Thus, in the process of the present invention, it is preferred to use a hydroisomerization catalyst which is essentially free of halogenated aluminum. Catalysts comprising crystalline aluminosilicates, such as 25 molecular sieves, mordenite, and layered crystalline aluminosilicates, are particularly preferred. It is preferred to use one or more hydrocarbon components with the crystalline aluminosilicate. Palladium and platinum are preferred hydrogenation components. Preferred catalysts comprising crystalline aluminosilicate and a hydrogenation component such as palladium or others are described in patent applications Ser. Nos. 776,733 and 839,999, which applications are incorporated by reference into the present patent application, particularly those portions of the afore-identified applications disclosing catalyst compositions. Preferred aluminosilicate-containing catalysts for use in the isomerization zone include catalysts comprising a 30 layered clay-type aluminosilicate cracking component, with 0.01 to 2.0 weight percent, based on said cracking component and calculated as the metal, of a hydrogenating component selected from platinum, palladium, iridium, ruthenium and rhodium, and also with 0.01 to 5.0 weight percent, based on said cracking component and calculated as the metal, of a hydrogenating component selected from tungsten and chromium. Particularly preferred hydroisomerization catalysts are those as described above wherein the 35 hydrogenating components are palladium and chromium. In the present specification, oxides and other compounds of metals are to be considered as included in reference to a metal simply as an element, i.e., chromium includes the use of chromium in compound forms such as chromium oxide.

Preferred catalysts for use in the C₄ disproportionation reaction zone are catalytic masses having a component with alkane dehydrogenation activity and a second component with olefin disproportionation activity, for example, catalytic masses comprising a Group VIII metal component and a Group VIB metal component. Particularly preferred C₄ disproportionation catalysts include catalytic masses comprising a noble metal on a refractory support and a Group VIB metal or metal compound on a refractory support, for example a catalytic mass comprising platinum on alu-

mina and tungsten or tungsten oxide on silica. Preferred temperatures for the disproportionation of butanes using the above-indicated catalytic masses are between about 400°-850°F. and more preferably 5 between 650°-799°F. Pressure maintained in the disproportionation reaction zone is preferably between atmospheric and 2,500 psia, and still more preferably between 100 and 1,500 psia. In addition to the preferred relatively low temperature for hydrocarbon disproportionation, we have found that it is preferable to carry out the disproportionation reaction in the presence of no more than a few weight percent olefins, preferably less than 5 weight percent olefins. Preferred 10 conditions for the disproportionation of saturated hydrocarbons such as butane or hexane are further discussed in commonly assigned applications Ser. Nos. 3,303 and 3,306, the disclosures of which applications are incorporated by reference into the present application.

In a commonly assigned application of Robert P. Sieg, filed the same day as the present application and titled "Hexane Conversion," a similar process is described wherein a C₆-rich hydrocarbon fraction is isomerized, preferably followed by C₆ disproportionation and C₄ disproportionation. The present application is directed to C₆ isomerization followed by C₄ disproportionation and, among other features, is based upon our surprising finding that very high yields of isopentane are obtained using the C₆ isomerization-C₄ disproportionation combination, with the C₆ disproportionation zone eliminated.

BRIEF DESCRIPTION OF THE DRAWING

35 The drawing is a schematic process flow diagram illustrating preferred embodiments of the present invention.

DETAILED DESCRIPTION OF THE DRAWING

40 Referring now more particularly to the drawing, a C₆-rich hydrocarbon stream is fed via lines 1 and 3 to isomerization zone 4. The C₆ fraction or cut can be obtained from the effluent from a catalytic reforming process and advantageously upgraded in the process of 45 the present invention to isopentane. However, the process combination of the present invention has particular application to straight run hydrocarbon C₆-rich fractions containing organic sulfur compounds, usually in an amount between about 5 ppm and 300 ppm, calculated as sulfur by weight.

The C₆-rich hydrocarbon fraction is isomerized in the presence of hydrogen using a hydroisomerization catalyst which preferably comprises a crystalline aluminosilicate together with a hydrogenation component such as palladium or platinum. Preferred operating conditions for the C₆ isomerization include a hydrogen gas rate in the range of 1,000 to 5,000 SCF/b., preferably 1,500 to 2,000 SCF/b.; space velocities in the range of about 0.1 to 20 liquid volumes per hour per volume of catalyst, preferably 1.0 to 5.0 LHSV; temperatures in the range of about 200°-800°F., preferably 250° to 750°F.; and pressures within the range of atmospheric to 3,000 psig, preferably in the range of 500-800 psig.

In addition to isomerizing normal hexane in isomerization zone 4, normal pentane derived from dispro-

portionation zone 16 is also isomerized in zone 4. As shown in the drawing, normal pentane from the disproportionation zone is recycled via line 2 and then introduced via line 3 to the isomerization zone. After stripping hydrogen sulfide from the isomerization reaction zone effluent and/or removing hydrogen sulfide by other methods, the isomerization effluent hydrocarbons are fed via lines 5 and 7 to fractionation zone 8.

Fractionation zone 8 typically consists of 3 to 8 distillation columns used to separate the various components obtained both from isomerization in zone 4 and disproportionation in zone 16, according to the preferred embodiment illustrated in the drawing. As indicated previously, the fractionation zone can have a varying number of distillation columns, and it is preferred to use common fractionation facilities for at least part of the separation of effluent hydrocarbons from isomerization zone 4 and disproportionation zone 16. It is particularly preferred to carry out the fractionation of normal pentane from C_6 alkanes in the same fractionation column for effluent hydrocarbons from disproportionation zone 16 and isomerization zone 4.

C_4 alkanes are removed from the fractionation zone via line 15 and fed to disproportionation zone 16 via line 15. The C_4 hydrocarbons are disproportionated at least in part to obtain normal pentane, propane and hexanes. Effluent hydrocarbons including normal pentane are removed from disproportionation zone 16 via line 17 and passed via lines 6 and 7 to fractionation zone 8.

In fractionation zone 8 normal pentane is separated. The normal pentane is passed via line 2 and line 3 to isomerization zone 4.

In isomerization zone 4, the normal pentane derived from disproportionation zone 16 is isomerized to isopentane which is ultimately fractionated from the isomerization zone effluent hydrocarbons and recovered as a product withdrawn via line 18.

Preferably the feed to disproportionation zone 16 is a mixture of iC_4 and nC_4 withdrawn via line 15 from fractionation zone 8. However, a portion or substantially all of the iC_4 can be withdrawn from zone 8 via line 9. Instead of upgrading the iC_4 in disproportionation zone 16, the separately withdrawn iC_4 in line 9 can be fed to an alkylation plant for reaction with olefins to produce high-octane gasoline.

Propane and other light gases formed in isomerization zone 4 and also in disproportionation zone 16 are removed from the effluent hydrocarbons from these two respective zones by separation in zone 8.

Preferably, common fractionation facilities are used to separate the propane and other light gases generated in disproportionation zone 16 and in isomerization zone 4, particularly when the isomerization is carried out at a high temperature, for example in excess of 700° or 750°F., so as to generate substantial amounts of propane and other light hydrocarbons. When the isomerization zone is operated at relatively mild conditions, for example below 700°F., and with only 1 or 2 percent or less weight percent propane produced in isomerization zone 4, depropanizing the effluent hydrocarbons from the isomerization zone could advantageously be carried out separate from the depropanizing of the effluent hydrocarbons from disproportionation zones 12 and 16.

Particularly preferred temperatures for the isomerization zone using the preferred Pd-Cr-crystalline clay-type layered aluminosilicate catalyst are about 650°-750°F. At these temperatures for this catalyst, we have found high isomerization yields and high conversion of hexane (see Table I hereinbelow). Isomerization at these preferred conditions results in surprisingly high yields of iC₅ when carried out in cooperation with C₄ disproportionation (see Table III hereinbelow).

25 Some heavier hydrocarbons, i.e., C_7^+ hydrocarbons, are formed in disproportionation zone 16. These heavier hydrocarbons are withdrawn from fractionation zone 8 via line 20. The C_7^+ hydrocarbons can be advantageously used as a feedstock for catalytic reforming to produce high-octane gasoline, for example by reforming using a platinum-rhenium on alumina catalyst. The C_7^+ hydrocarbons alternately can be passed at least in part via lines 22, 2, and 3 to isomerization zone 4. The C_7^+ hydrocarbons are suitable feedstock for isomerization and cracking to lower hydrocarbons including normal butane and isopentane.

EXAMPLES

Example 1

40 A C₆-rich fraction was desulfurized from 100 ppm S to less than 0.1 ppm S under the following reaction conditions:

45	Conditions:	
	T, °F.	700
	P, psig	800
	LHSV	1.0
45	Catalyst composition:	Pd-Cr-Layered crystalline aluminosilicate
	Hydrogen, SCF/bbl.	10,000

Example 2.

Using the same Pd-Cr-layered aluminosilicate catalyst as in Example 1, a C₆-rich fraction free of sulfur was isomerized at 800 psig, LHSV = 1.0 and hydrogen rate = 17,000 SCF/bbl. of feed, with the results as shown in Table I.

TABLE I.—ISOMERIZATION OF SYNTHETIC NAPHTHALENE

Example 3

The data tabulated in Table II below illustrate the results obtained in disproportionating normal butane by contacting normal butane with an alkane disproportionation catalyst mass under the following conditions:

Volume of Catalyst in Reactor: 9 cubic centimeters (cc.)

Type of Catalyst:

2 cc. of 0.5 wt.% Pt; 0.5 wt.% Re; 0.5 wt.% Li on Al_2O_3

7 cc of 8.0 wt.% WO_3 on SiO_2

Both types of catalyst particles were 28 to 60 Tyler mesh size.

Operating Conditions:

Temperature: 650°, 700°, 750°, 800°, 875° F.

Pressure: 900 psig

Feed rate: 9 cc./hour

¹Successive runs, of several hours each with no regeneration in between, were made at the temperatures specified, except that the catalyst was reactivated by flushing the catalyst overnight with hydrogen before the run at 875° F.

As can be seen from the data tabulated in Table II, the ultimate yield of C_5^+ decreases considerably in moving from particularly preferred temperatures below 800°F. to temperatures in excess of 800°F. as, for example, temperatures as high as 875°F., where the ultimate yield of C_5^+ drops to about 42% vs. approximately 57% at 750°F. More importantly, the yield of nC_5 is

in $\text{C}_5\text{--C}_9$ range) ³						
ΣC_5^+ Ultimate Yield = $\Sigma \text{C}_5^+ / (\Sigma \text{C}_1\text{--C}_3 + \Sigma \text{C}_5^+)$						

¹All olefins analyses are from an approximate chromatographic analysis.

²The decrease in branching with decreasing temperature indicates the process of the present invention is more selective for pure disproportionation without isomerization at lower temperatures. This attribute is important when it is desired to produce n-paraffins, as, for example, in wax production.

³N.M. = not measured because products were hydrogenated prior to analysis.

Example 4

Table III below tabulates the surprisingly high yield of iC_5 (68 wt. percent) with no C_6 disproportionation zone. Table III is based on laboratory data for isomerization and C_4 disproportionation and calculations based on the indicated recycle from fractionation zone 8.

Although various embodiments of the invention have been described, it is to be understood that they are meant to be illustrative only and not limiting. Certain features may be changed without departing from the spirit or scope of the present invention. It is apparent that the present invention has broad application to combined C_5 , C_6 alkane isomerization and C_4 disproportionation to produce isopentane. Accordingly, the invention is not to be construed as limited to the specific embodiments or examples discussed, but only as defined in the appended claims or substantial equivalents of the claims.

55 What is claimed is:

1. A process for producing isopentane which comprises:
  - a. isomerizing a C_6 -rich hydrocarbon fraction containing C_4 and C_5 hydrocarbons in an isomerization zone to obtain at least isopentane and C_4 alkanes;
  - b. fractionating the isopentane from the C_4 alkanes to obtain an isopentane product;

- c. disproportionating at least a portion of the C₄ alkanes in a C₄ disproportionation zone by contacting the C₄ alkane with a catalyst comprising a Group VIII metal or metal compound and a Group VIB metal or metal compound at a temperature between 400°F. and 850°F. to obtain at least n-pentane and C₃ hydrocarbons; and
  - d. isomerizing the n-pentane to iso-pentane in the isomerization zone.
2. A process in accordance with claim 1 wherein the C₆-rich hydrocarbon feed to the isomerization zone contains at least 5 ppm sulfur present as organic sulfur compounds and the isomerization is carried out using a sulfactive isomerization catalyst at conditions sufficient to convert the organic sulfur compounds to H₂S and hydrocarbons, and H₂S is separated from the C₄ alkanes from the isomerization zone before the C₄ alkanes are fed to the disproportionation zone.

3. A process in accordance with claim 1 wherein common fractionation facilities are used at least in part for effluent hydrocarbons from the isomerization zone and effluent hydrocarbons from the C₄ disproportionation zone.

4. A process in accordance with claim 3 wherein the same fractionation column is used for the fractionation of normal pentane from C₆ alkanes present as a mixture in effluent hydrocarbons from both the isomerization zone and the C₄ disproportionation zone.

5. A process in accordance with claim 1 wherein the C₆-rich hydrocarbon stream fed to the isomerization zone is a straight run fraction obtained by fractionating a C₆-rich cut from crude oil.

6. A process in accordance with claim 1 wherein the catalyst used in the isomerization zone is substantially free of halogenated aluminum.

7. A process in accordance with claim 1 wherein the isomerization catalyst comprises palladium or platinum and a crystalline aluminosilicate material.

8. A process in accordance with claim 1 wherein the isomerization catalyst comprises 0.05 to 5.0 weight

percent palladium and 0.05 to 5.0 weight percent chromium on a layered clay-type crystalline aluminosilicate material.

9. A process in accordance with claim 1 wherein the disproportionation reaction is carried out at a temperature between 400° and 850°F. using a catalyst comprising a noble metal on a refractory support and a Group VIB metal compound on a refractory support.

10. A process in accordance with claim 1 wherein the disproportionation reaction comprises contacting the C₄ alkanes with a catalytic mass comprising platinum on alumina and tungsten or tungsten oxide on silica at a temperature between about 650° and 850°F. and a pressure between about 100 psia and 1,500 psia.

11. A process in accordance with claim 10 wherein the olefin concentration in the disproportionation reaction zone is maintained below about 5 volume percent.

12. A process for producing isopentane from C₆ hydrocarbons which comprises:

a. isomerizing a C₆-rich hydrocarbon stream containing C₄ and C₅ hydrocarbons and between 5 and 500 ppm organic sulfur compounds in an isomerization zone by contacting the C₆-rich hydrocarbons with a sulfactive isomerization catalyst at a hydrogen partial pressure between about 100 and 1,500 psig and a temperature between about 200°F. and 800°F. to obtain a C₄-rich effluent stream containing less than 0.1 ppm sulfur present as organic sulfur compounds,

b. disproportionating at least a portion of the C₄-rich effluent stream by contacting the C₄ hydrocarbons with a catalyst comprising platinum on a refractory support and a Group VIB metal or metal oxide on a refractory support at a temperature between 400° and 850°F. to obtain a hydrocarbon stream comprising propane, normal pentane and C₆ hydrocarbons,

c. isomerizing at least a portion of the normal pentane from the C₄ disproportionation in the isomerization zone to obtain isopentane.
